UNITED STATES PATENT OFFICE

KIICHIRO YANO, OF OAZA, CHIKAMI-MURA, OCHI-GUN, EHIME-KEN, JAPAN.

MECHANICAL STOKER FOR PROMOTING SMOKELESS COMBUSTION.

1,116,664.

Specification of Letters Patent. Patented Nov. 10, 1914.

Application filed June 26, 1912. Serial No. 705,905.

To all whom it may concern:

Be it known that I, KIICHIRO YANO, engineer, of No. 9 Oshinden, Oaza, Chikami-Mura, Ochi-gun, Ehime-ken, Empire of Japan, have invented an Improvement in 5 Mechanical Stokers for Promoting Smokeless Combustion, of which the following is a specification.

My invention relates to improvements in 10 furnaces, and seeks to provide an arrangement for promoting smokeless and efficient combustion in furnaces for steam boilers, and other purposes.

The invention relates more particularly 15 to that class of furnaces wherein a supply of fuel is first admitted to a conveyer from which it is passed to the grate bars, to promote the ignition and combustion of the gases evolved from the fuel.

To this end my conveyer is of the type 20 that coöperates with the reciprocating movements of the grate bars, which motion causes the fuel to pass gradually from the dead plate to the grate of the furnace, so as to cause the same to be heated, vaporized 25 and ignited during the movement. Such ignited fuel is spread evenly over the surfaces of the grate bars, and is thoroughly mixed by imparting to the grate bars three 30 staged reciprocating motions, all as more fully hereinafter explained.

My invention has for its object to promote smokeless combustion of various kinds of coals, and further, to prevent any objectionable adhesion of fused clinkers upon 35 the face of the brick work, and to economize the fuel to a great extent.

In order that my invention may be easily understood and readily carried into practical effect I have appended hereunto six 40 sheets of drawings.

In these drawings: Figure 1 is a longitudinal section of one form of my invention as applied to a Cornish boiler. Fig. 2 is a 45 front view of same. Fig. 3 is a transverse section. Fig. 4 is a plan view partially in section. Fig. 5 is a detail of the cams for moving the grate bars. Fig. 6 is a rear view of the cams shown in Fig. 5. Fig. 7 is a detail of the grate bars, grate movers and cams. Fig. 8 is a perspective view of same. Fig. 9 is a detail view showing the relative positions of the cams and grate bars at the end of the first stage of the 50 movement of the cams. Fig. 10 is a similar view showing the positions at the end of the

second stage of their movement. Fig. 11 is a similar view showing the third stage of their movements. Fig. 12 illustrates the invention as applied to a water tube boiler.

Two arms 1, of suitable length are arranged on the sides of the furnace A, a rectangular portion of each arm being cut away so as to form slots 2, 2, adapted to receive therein two grate movers 3, 3', as shown 65 in Figs. 1, 4, 7, and 8. Mounted on the arms 1, is a rotating shaft 4, which is driven by the worm gears, or other like gears, from the belt driven shaft 6, upon which the stepped pulley 5 is mounted as shown in Figs. 2 and 70 4. Rigidly secured at the ends of the shaft 4, and in close proximity to the outer faces of the bearing arms 1, are two cams 7, both faces of which cams are provided with projecting lugs or pawls 8, 8' at their axial 75 center portions as shown in Figs. 5 and 6. These cams are also provided with V-shaped projections or raised forked cam-ways on their inner faces as shown in Fig. 5; the outer-leg 9 of the V-shaped projections extending along the edge of the cam while the inner leg 9' extends inwardly as illustrated.

At both ends of the front grate mover 3, i. e. the mover located nearer to the axes 80 of said cams, a roller 10 is provided while the rear grate mover 3' is provided with reversing links 11, in addition to rollers or end rings 10' as shown in Figs. 8 and 9. By means of these arrangements the grate bars 90 in the furnace are given reciprocating motion in three particular stages, viz: In the first stage of the movement of the cams 7, the outer edges of the pawls 8 engage with the corresponding peripheries of the end 95 rings or rollers 10 of the grate mover 3, thereby causing the latter to move backward or toward the furnace, and also moving the grate mover 3' in a similar direction, see Fig. 9. In the second stage of the movement of the cams 7, the outer rims of the legs 9 come into engagement with the corresponding surfaces of the rear grate mover 3', and thus prevent the latter from moving forward while the inner rim of the leg 9' 100 will then act upon the roller 10 of the front mover and force same forward; and consequently the front grate mover 3 moves outward from the furnace as illustrated in Fig. 10. In the third stage of movement of 105 the cams 7, the outer pawls 8' engage with the rollers 11' on the reversing links 11

thus moving the rear grate mover 3' forward or outwardly from the furnace.

The present invention contemplates the use of two rows of grate bars arranged in 5 stepped order, viz. front grate bars 12, and rear grate bars 12'. The former have suitable cutaway portions or recesses in their lower surfaces at the front ends adapted to alternately engage with one or the other of 10 the grate movers 3, 3'; that is to say, while one grate bar of the front rank rests on top of the front mover 3, the next adjacent bar will be carried upon the rear mover 3' and the next adjacent bar in turn will be carried by the front mover 3, and so on. Thus 15 it will be seen from this construction that the movement of the bars engaging with the front mover 3 will not be disturbed by the movement of the bars engaging with the rear mover 3'.

As shown in Fig. 7, the front ends of the bars engaging with the rear mover 3' are adjacent to the inner face of the front mover 3, so that when the latter is moved in a backward direction, or toward the furnace, the rear mover will at the same time be moved 25 in that direction.

To insure even distribution of the fuel, I provide upon each of the front row of grate 30 bars projections or pyramidal knobs 13 as shown in Fig. 4, which, as the bars reciprocate, act as mixers and disperse the fuel evenly over the surface of the grate bars.

At the lower rear end of each of the front 35 grate bars 12, a small lug is provided, which engages with a corresponding cut away portion or groove 15, formed in the upper faces of each bar of the rear grate 12' as shown in Fig. 1.

40 In practice it is found that the fuel is liable to be largely consumed in the front grate 12 before it is passed onto the rear grate 12' leaving on this latter grate only small quantities of soft coke which is liable 45 to admit surplus air into the furnace, thereby adversely affecting the efficiency of the furnace. To obviate this defect, the grooves 15 in the rear grate bars are made longer than the width of the lug 14, so that the 50 travel of the front grate is greater than that of the rear grate. This insures the fuels accumulating to a larger extent upon the rear grate, and consequently prevents the admittance of an excess of air into the rear 55 of the furnace. 16 is an ash-pit tray upon which said rear grate bars 12' are mounted. This tray serves as a partition for separating half burnt fuels dropping through the spaces between the grate bars from the 60 already burnt up fuels or ashes falling over the back ends of the rear grate bars 12'. 17 and 17' are two sliding doors fitted respectively at the top and bottom of the said tray 16 as shown in the drawing. With 65 smaller flues where insufficient room is

allowed for the installation of such trays, a suitable flue protector may be used so as to utilize the same as a support for the rear grate.

Above the front portion of the front grate 70 12 is placed a suitable dead plate 18, having pyramidal or other suitable projection 19 preferably in the middle portion of the rear end. 20 is a series of obliquely arranged 75 air passages extending oppositely from and parallel to the sides of said pyramidal projection 19 as shown in Fig. 4.

The pyramidal projection 19, serves to eliminate the usual tendency of the fuel to accumulate thicker in the center than it does 80 at the sides of the grate of the furnace. The oblique perforations 20 serve as air passages for igniting the fuel before it falls upon the surface of the grate bars.

19' is a rib extending across the entire 85 width of the lower surface of the dead plate 18 which serves to return or force back any burning fuel and thus encourages and expedites the ignition of fresh fuel falling on top 90 of the dead plate. This will leave no useless space between the dead plate and the grate bars.

Movably mounted upon the dead plate 18 is a fuel conveyer which consists of the casing 21, the back wall of which is inclined 95 and has a number of air passages 23 therethrough and is provided with one or more buckets 24 according to the size of the furnace as shown in Figs. 1, 2, and 4. This fuel conveyer serves not only as a forwarder 100 of the fuel but also as a coking plate or chamber.

Two lugs 25 are arranged in the middle bottom portion of the part of the casing 21. Each lug is provided with a vertical aperture 26 which is adapted to receive a suitable connecting rod 29, which rod engages at its lower end with one of a specially elongated grate bar of the front grate and thus reciprocates the casing. To adjust the position of the connecting rod 29 and consequently the position of the casing 21 relatively to the dead plate, a number of small blocks 28 are used to be inserted in the space between the rod 29 and two lugs 27 110 which are provided on the upper surfaces of the front end portion of the said elongated bar, as shown in Figs. 1, 4 and 7. 30 is a suitable screw bolt holding the said connecting rod 29 in the aperture 26. By this construction the position of the said connecting rod will be readily adjusted by increasing or decreasing the number of the said adjusting blocks 28 and consequently the movement of the conveyer will be regulated at will, which 120 in turn regulates the feeding of the fuel.

Above the dead plate and in the front part of the furnace is an internally mounted crown plate 31 which is adapted to serve 125 as a hot draft creating member by heating 130

the air or steam from the injector 32. This injector may consist of a depending tube at the front of the furnace, the lower end opening into the furnace as illustrated at 5 Fig. 1.

The feeding hopper 33, which is fitted with a sliding door 34, opens directly to the conveyer below, and the vaporized matters evolved from the fuels above the coking 10 plate will be thoroughly mixed with the jets of heated air or steam issuing from the injector 32 whereby the complete ignition of an inflammable gas is insured and the products of combustion are caused to issue in a 15 long smokeless flame.

To apply my invention to the furnace of a water tube boiler, or to other furnaces of a like class, I provide as shown in Fig. 12, suitable partitions or walls such as 35, 36, in 20 the back of the ash pit. I also provide a suitable water tank 37. In order to keep the ash-pit entirely sealed with water, the lower end of the said wall 36 is immersed in the water as shown, so that the ashes or 25 clinkers can be taken out without admitting any surplus air into the furnace.

To prevent fused fuel or clinker from adhering upon the brick work, chrome bricks may be used at the places where the clinkers 30 are generally found to adhere with the brick work, for instance as with the crown plate or upon the grate bars.

From the above description, it will be understood that the coal fed into the hopper 35 will be conducted through the adjusting door 34, to the point above the coking

plate which forms the front part of the conveyer. When the furnace is first lighted it is necessary to fill up the said coking portion with already lignited fuel prior to the 40 feeding of the hopper, and therefore the fuel falling through the hopper will be highly heated at the point above the coking plate where it vaporizes and by virtue of the movement of the conveyer passes gradually to the dead plate to be lignited thereon before it is carried down to the top of the grate bars. 45

Having now fully described my invention, what I claim is:

In a combustion apparatus, the combination of two grate movers, a set of bars connected with each of said movers, means for moving said movers inwardly together, and moving said movers outwardly independently of each other, a dead plate mounted above said grate bars and having a downwardly projecting lug extending across the same at some distance from the inner end, 50 co-acting with said bars and an upwardly extending lug for spreading the fuel, and also having a series of air passages in the inner end thereof, and a fuel conveyer mounted on said plate and arranged for moving the fuel longitudinally thereof. 55

In testimony whereof I affix my signature in presence of two witnesses.

KIICHIRO YANO.
